United States Patent

Des. 235,276
Patented June 3, 1975

235,276

CONTACT PRINTER

Ronald Keith Dodson, Portland, and Donald H. McCauley, Beaverton, Oreg., assignors to GAF Corporation, New York, N.Y.

Filed July 23, 1973, Ser. No. 382,001

Term of patent 14 years

Int. Cl. D16—04

U.S. Cl. D61—1 Q

FIG. 1 is a top front and left side perspective view of a contact printer showing our new design;

FIG. 2 is a top front and right side perspective view thereof.

The rear of the contact printer, not shown, is substantially plain and unornamented similar to the sides shown.

We claim:

The ornamental design for a contact printer, substantially as shown.
